UNITED STATES PATENT OFFICE.

JACK GREEN, OF NORFOLK, VIRGINIA.

CLAMP FOR CONTAINERS.

Application filed December 3, 1926. Serial No. 152,444.

This invention relates to a clamp designed more particularly for securing in fixed position containers of a type and size which would otherwise be difficult to secure and hold. In certain types of containers, particularly metal containers of large size, great difficulty has been heretofore experienced in fixing them temporarily in a perfectly rigid position in order to permit necessary work thereon as, for example, the removal of the sealing plugs or other fittings which in a sustained use of the container become practically frozen in place. Containers of this type, owing to their bulk and general circular form, are very difficult to fix with sufficient rigidity to permit the necessary operations, particularly when, as will be evident, it is highly desirable that the clamping or fixing means be capable of simple application and disconnection to avoid loss of time and labor incident to the use of complicated securing means.

The present invention is directed to a clamp designed particularly for use with containers of this type, with the parts so constructed and arranged as to provide for extremely simple and quick application of the clamp and an even more expeditious separation of the clamp.

30 The invention is illustrated in the accompanying drawings in which:

Figure 1 is a plan view showing the clamp applied in position.

Figure 2 is a front elevation of the same.

35 Figure 3 is a perspective view of the operative end of the locking lever.

Figure 4 is a section through the lever on line 4-4 of Figure 1.

The improved clamp comprises clamping arms 1 and 2 preferably metallic and of appropriate width and thickness for the purpose designed. The respective arms, which are in curved formation, are carried by and fixed relative to any appropriate support. Merely for convenience of illustration, such support is shown as a bracket 4 secured to a fixture and having angle braces 6.

Secured to one of the clamping arms, as 1, preferably near its free end is one terminal of a chain 7 made up of substantially rectangular links, the connection to the arm being, if desired, through a plate 8. A similar chain 9 is secured to the other arm 2 through the medium of a plate 10, the final free link 11 of the chain 9 being preferably

of greater dimensions than the remaining links.

A locking lever indicated at 12 is carried by the link 11, this lever comprising a rod 13 having a terminal eye 14 to loosely receive the link 11. A locking plate 15 is secured upon the rod or handle 13 immediately above the terminal eye 14, the plate occupying a plane directly transverse the handle. 65

In that portion of the plate on the side of the handle toward the link 11, the edge of the plate is cut away to provide recesses 16 and a central guide projection 17 adapted, when the lever is in operative or locking position, to receive the respective bars of the link 11 with the projection 17 accurately guiding the lever to insure that the bars of the link shall enter the recesses 16. 70

The locking plate on the opposite side 75 of the handle is slightly reduced in width and formed with a slot 18 opening through the free edge of the plate and extending longitudinally of such plate toward the handle. This slot 18 is of a length corresponding to 80 the width of one of the links of chain 7 and of a width corresponding approximately, that is slightly exceeding the thickness of the metal of the link. Rearwardly of the free edge of the reduced portion of the locking plate, the latter is formed with a recess 19 transverse the slot 18 and formed to accurately cooperate with an end wall of a link of the chain 7. Thus the chain 7 may 85 cooperate with the locking plate by introducing a link into the slot 18 with the next adjacent link toward the free end of the chain having its end wall fitting in the recess 19. The link thus fitted in the recess 19 is, of course, transverse the locking plate and 90 thereby prevents endwise movement of the chain relative to the locking plate in one direction, though it is to be understood that the depth of the recess 19 is such as to merely hold this transverse link in proper 95 position without preventing a separation of the chain and locking plate under a pull on the chain of sufficient strength to dislodge the link in the slot 18.

In the use of the clamp, the container 20 105 is positioned within the arms 1 and 2. The handle 13 of the locking lever is turned outwardly into a position approximately at right angles to that shown in Figure 1 and the appropriate link of the chain 7, that is 110

the link which will draw the arms comparatively snug about the container, is passed flatwise into the slot 18 so that the next adjacent link towards the free end of the chain 5 rests crosswise of the locking plate with its end wall in the recess 19. Pressure is then exerted upon the free end of the handle 13, moving the same into substantially the position shown in Figure 1. This movement will 10 result in a relative change in position of the end of the handle connected to the link 11 and that portion of the locking plate to which the chain 7 has been connected, moving the respective ends of the chains 7 and 9 15 in opposite directions and correspondingly bind the arms 1 and 2 upon the container 20. The movement of the locking lever is continued until the side bars of the link 11 are embraced in the recesses 16 of the locking 20 plate to thereby prevent any possibility of a lateral swing of the lever and a loosening of the clamp. The lever may be temporarily fixed in such clamping relation as, for example, through the medium of a chain 21 secured at one terminal of a fixture and arranged to permit an appropriate link thereof to engage a hook 22 on the handle 13 of the locking lever.

When desiring to release the clamp, all 30 that is necessary is to exert a sufficient pull upon the free end of the chain 7 to dislodge the holding link seated in the recess 19 and at the same time displace the link in the slot 18. This immediately frees both arms 1 and 35 2 and releases the clamp.

It is obvious that within the limits of the clamping action of the arms 1 and 2, the clamp is completely adjustable for any link 40 of the chain 7 may be made the operative holding link in connection with the lever and as it is intended that this chain shall be of appropriate length, it is apparent that the clamping effect may with equal facility be applied to containers which may be completely 45 embraced by the arms 1 and 2 or of such size as to be only partially embraced by said arms.

The clamp of the present invention is admirably designed for the purpose intended 50 and it is to be noted avoids what may be termed a positive connection for tightening the clamp. That is to say, no hooks for cooperation with the chain 7 are used as obviously the use of such would necessitate the 55 return of the lever to an inoperative position before releasing the clamp, thus necessitating a loss of time.

What I claim as new is:

1. A clamp comprising clamping arms, a 60 chain connected to each of said arms, and a locking lever carried by one of said chains, said lever being formed to receive and cooperate with two adjacent links of the other of said chains and hold one of said links 65 transverse the other for locking purposes

and being further formed to cooperate with a link of the chain with which it is connected to maintain the alignment of the lever.

2. A clamp comprising clamping arms, a chain connected to one of said arms, and a locking lever carried by the other of said arms, said lever being formed to receive and cooperate with two adjacent links of said chain and hold one of said links transverse the other for locking purposes, the chain 75 being separable from the lever by a pull on the chain to dislodge the link at right angles to the lever.

3. A clamp comprising clamping arms arranged to embrace an object to be clamped, a chain connected to one of the arms, a second chain connected to the other of said arms, and a locking lever carried by the second chain and formed to permit the bodily insertion of a link of the first mentioned chain and to hold an adjacent link of said first mentioned chain at right angles to the inserted link, said lever being movable to carry the respective ends of the chains toward each other to exert a clamping movement on the arms.

4. A clamp comprising clamping arms, a locking lever movably connected to one of said arms, a locking plate carried by said lever and formed with a slot arranged longitudinally of the plate and a recess disposed transversely of the slot, and a chain connected to the other of said clamping arms with its links of a size to seat in said slot and with an end wall to cooperate with the recess to arrange such link transverse the locking plate.

5. A clamp comprising clamping arms, a locking lever movably connected to one of said arms, a locking plate carried by the lever, a chain connected to the other of said arms, said locking plate being formed to receive one of the links of said chain in the longitudinal plane of the locking plate and hold the next adjacent link of said chain at right angles to the locking plate, means to operate the locking lever to exert an endwise pull on the chain, and means to hold the locking lever in locking position.

6. A clamp comprising clamping arms, a link chain connected to one of said arms, a locking lever connected to the terminal link of said chain, a second chain carried by the other of said arms, a locking plate carried by the lever formed to cooperate with adjacent links of said last mentioned chain to interconnect the chain and plate, said lever being operable on the first mentioned chain to exert an endwise pull on the respective chains to bind the clamping lever, and means on the locking plate to cooperate with the final link of the first mentioned chain to prevent lateral play of the lever when in locking position.

7. A clamp comprising clamping arms, a link chain connected to one of said arms, a

locking lever connected to the terminal link of said chain, a second chain carried by the other of said arms, a locking plate carried by the lever formed to cooperate with adjacent 5 links of said last mentioned chain to interconnect the chain and plate, said lever being operable on the first mentioned chain to exert an endwise pull on the respective chains to bind the clamping lever, said locking plate 10 being formed with recesses to receive the side bars of the final link of the first mentioned chain when the lever is in locking position.

8. A clamp comprising clamping arms, a 15 link chain connected to one of said arms, a locking lever connected to the terminal link

of said chain, a second chain carried by the other of said arms, a locking plate carried by the lever formed to cooperate with adjacent links of said last mentioned chain to 20 interconnect the chain and plate, said lever being operable on the first mentioned chain to exert an endwise pull on the respective chains to bind the clamping lever, said locking plate being formed with recesses to receive the side bars of the final link of the first mentioned chain when the lever is in locking position, and with a center projection serving to guide the lever into cooperation with said final link. 25

In testimony whereof I affix my signature.
JACK GREEN. [L.S.]
